UNITED STATES PATENT OFFICE.

CARL ERNST PREUSSE, OF REUDNITZ, LEIPSIC, SAXONY, GERMANY.

BOOK-STAPLING MACHINE.

SPECIFICATION forming part of Letters Patent No. 399,555, dated March 12, 1889.

Application filed May 5, 1887. Serial No. 287,293. (No model.) Patented in Germany January 26, 1886, No. 36,510, and May 18, 1886, No. 37,744.

To all whom it may concern:

Be it known that I, CARL ERNST PREUSSE, a subject of the King of Saxony, Germany, residing at the city of Reudnitz, Leipsic, in 5 the Kingdom of Saxony, Germany, have invented certain new and useful Improvements in Book-Stapling Machines, (for which Letters Patent have heretofore been granted to me in Germany, dated January 26, 1886, No. 10 36,510, and May 18, 1886, No. 37,744,) of which the following is a specification.

This invention relates to certain new and useful improvements in the book-stapling machine for which United States Letters Patent 15 No. 298,117 were issued to me on the 6th day of May, 1884; and this invention relates especially to the mechanism for shifting the wire, the construction of the operating-lever and the block, mandrel, or die over which the pieces 20 of wire are bent.

The invention consists in the combination, with the driver-slide, of improved mechanism for feeding the wire for shifting the mandrel and the hand-lever for operating the machine.

The invention also consists in the construction and combination of parts and details, as will be fully described and set forth herein-after, and finally pointed out in the claims.

30 In the accompanying drawings, Figure 1 is a perspective view of my improved book-stapling machine. Fig. 2 is a front elevation of the driver-slide and wire-shifter, parts being in section. Fig. 3 is a side view of the

35 same. Fig. 4 is a front view of the same, showing the parts in different positions, parts being in section. Figs. 5, 6, and 7 are detail front views of the same, parts being broken out and others in section. Fig. 8 is a detail 40 front view of the cutter and shaper. Fig. 9 is a side view of the same. Fig. 10 is a perspective view of a modification of my improved machine. Fig. 11 is a front end view of the same, parts being in section. Fig. 12 is a front view of the same, the parts being in 45 different positions and some being in section. Figs. 13 and 14 are detail front views of the driver-slide, cutter, and feeder in different positions, parts being in section.

50 Similar letters of reference indicate corresponding parts.

The driver-slide and the devices for cutting and bending the wire are constructed the same as in my patent, No. 298,117, referred to above.

55 The wire is fed by the following mechanism: When the machine is closed—that is, when it has just driven a staple—the feeder-slide *a* has the position shown in Figs. 4 and 5. If the machine is opened—that is, started to 60 make and drive a fresh staple—the driver-slide *b* rises and raises the link *c*, pivoted to the top of the driver-slide *b*, the lower end of said link being provided with a slot through which a pin on one end of a pivoted angle-lever, *d*, passes, a pin on the opposite end of said angle-lever passing into a slot in a cam-piece, *e*, pivoted to jaws on the top of the feeder-slide *a*, over which slide the wire is passed. The slide *Q* is provided with two blades, *n*, which 70 serve to cut off the wire, and also to bend the same over the die, block, or mandrel *r*, which is pressed by two springs, *f*, into the slot for the driver-slide in the plate *B*. The slide *Q* is provided with a notch or recess for receiving 75 one end of the angle-lever *p*, pivoted on arms of the fixed frame, and provided in its upper end with a pin which passes into an inclined slot, *y'*, of an arm, *y*, on the driver-slide *b*. The slide *Q* is provided with a downwardly-projecting fork, *i*, having its lower ends beveled to act on bevels *k* of the block or mandrel *r*.

80 The curved lever *A* is pivoted at *o*, and to its lower end, at the front of the machine, the handle-section *A'* is pivoted, which is held approximately in line with the lower shank of the lever *A* by the spring *s*.

85 The clinching-anvil *g*, which serves to press over or clinch the ends of the staple, is drawn 90 downward by a spring, *W*, secured to a pin on the anvil and a fixed pin on the frame, and pressed upon an end of a short lever, *t*, pivoted on the frame of the machine, the other end of said lever being below the handle part 95 *A'* of the lever *A*.

90 The operation is as follows: The ascending driver-slide *b* moves the feed-slide *a* to the right, and at the same time the cam-lever *e* is inclined, so that its cam end does not grip the wire passed over the slide. The descending driver-slide *b* swings the cam-lever *e* into a 100

vertical position, so that its cam end firmly 5
grips the wire on the slide *a*, which is moved
to the right, thereby feeding the wire under
the cutter, whereby the wire is cut and bent
over the mandrel to form a **U**-shaped staple.
The beveled ends of the fork *i*, acting on the
bevels *k* of the mandrel *r*, force said mandrel
out of the path or slot for the driver-slide in
the plate *B*, so as to permit said driver to act
on the staple. When the slide *Q* rises, the
springs *f* press the mandrel *r* back into the
path of the driver-slide, ready for forming the
next staple.

The machine is operated by pressing down
15 the handle-piece *A'* of the lever *A*. The spring
s is of such power that when the handle *A'*
is pressed down sufficiently to cut the wire,
form the staple, drive it through the paper, &c.,
said spring does not permit the handle *A'* to
20 turn on its pivot; but when more power is ex-
erted the handle part *A'* turns down on its
pivot and bends the spring *s*, and at the same
time said handle part *A'* acts on one end of
the lever *t*, causing the other end to force up-
25 ward the clinching-anvil *g*, the upper end of
which clinches the ends of the staple that has
been forced through the paper.

In place of providing the construction
shown in Figs. 1 to 6 for feeding the wire, the
30 construction shown in Figs. 10 to 14 may be
used. It consists of a lever-plate, *M*, pivoted
on the end of the machine and having a slot,
*b*², into which a pin, *b'*, on the driver-slide is
passed, whereby said lever-plate *M* is swung
35 on its pivot *m*. Lugs on the plate *M* act on
the pin on the angle-lever *d*, and said plate
M also operates the slide *Q*.

Having thus described my invention, I claim
as new and desire to secure by Letters Pat-
40 ent—

1. In a book-stapling machine, the combi-
nation, with a driver-slide, of a wire-feeding

slide, a cam-piece on said feeder-slide, and
mechanism, substantially as herein shown and
described, connecting said cam on the feeder-
slide with the driver-slide, substantially as set
forth.

2. In a book-stapling machine, the combi-
nation, with a driver-slide, of a slide having
blades, a mandrel provided with bevels, a fork
50 on the slide having the blades, which fork has
beveled ends that act on the bevels of the
mandrel, springs for holding said mandrel,
and mechanism for operating the slide having
the blades from the driver-slide, substan-
55 tially as herein shown and described.

3. In a book-stapling machine, the combi-
nation, with a driver-slide, of a wire-feeder
slide, a cam-piece on said feeder-slide, a slide
having blades, a mandrel, a slide having
60 blades and fork with beveled ends acting on
the mandrel, springs for holding the mandrel,
mechanism for operating the feeder-slide from
the driver-slide, and mechanism for operating
the slide having the blades from the driver-
slide, substantially as herein shown and de-
scribed.

4. In a book-stapling machine, the combi-
nation, with mechanism for driving staples,
of a lever for operating the said mechanism,
70 a handle part pivoted on said lever, a spring
held on the lever and handle section, a piv-
oted lever having one end below said handle
part, and a sliding anvil resting on the other
end of said lever, substantially as herein shown
75 and described.

In testimony whereof I have signed my name
to this specification in the presence of two sub-
scribing witnesses.

CARL ERNST PREUSSE.
